HINGED HANDLE CONNECTION FOR FLOOR TREATING MACHINE

Arthur W. Seyfried, Racine, Wis., assignor to S. C. Johnson & Son, Inc., Racine, Wis.

Application December 30, 1953, Serial No. 401,217

1 Claim. (Cl. 306—11)

This invention relates to a handle tensioning means for a floor-treating device. More particularly, it relates to a handle tensioning means for a handle attached by means of a forked bail to a floor-treating device which employs a rotary brush.

In a polishing or scrubbing machine employing a single brush as the only contact with the floor and which rotates about a vertical axis, there is a strong tendency for the device to move across the floor surface with an irregular or unsteady motion, commonly known as "wobble." Various methods have been advocated to eliminate this wobble, such as unique arrangements of the various component parts of the mechanism, or even the employment of two counter-rotating brushes to balance the brush torque. However, none of these methods have been successful, especially when the machine is operated with the handle at angles approaching the horizontal.

It is the object of this invention to provide a means of controlling this irregular and unsteady movement of a single rotary brush floor-treating device.

It is a further object of the invention to provide such a handle tensioning means which is easy to assemble and disassemble.

Another object of the invention is to provide a device which is simple and inexpensive to manufacture.

The invention contemplates a handle tensioning means by which the operator of the polisher or scrubber can easily control the machine and thus eliminate the wobbles, no matter what the vertical position of the handle.

Other objects will be apparent from the following specification.

The same reference characters have been used for designation of like parts throughout and in the drawings, in which:

Fig. 1 is a bottom view of a floor-treating device showing the bail in a horizontal position and the housing in dotted lines.

Fig. 2 is a sectional view of the tensioning assembly taken along the line 2—2 in Fig. 1 with the bail in a vertical position.

Fig. 3 is an exploded perspective view of the tensioning means.

Figs. 4, 5 and 6 illustrate, respectively, the end, side and top elevations of the lock washer used in the tensioning means.

Referring to the drawings, the floor-treating device employing the tensioning means of this invention comprises a handle (not shown) attached to a forked bail 10 which is attached to housing 11 by means of the tensioning assembly designated in Fig. 1 by the numeral 12. A bolt 13 extends substantially perpendicularly to bail 10 through an opening in housing 11 for attachment to bracket 14. Bracket 14 is rigidly affixed to the floor-treating device by any suitable means such as by screw 15 which engages frame member 16 of the housing.

Bolt 13 is threaded at its extremity and has a pair of parallel milled flats or keyways 17 extending for a substantial distance from the threaded portion toward bail

2

10. A stop 19 is permanently affixed on bolt 13 at a position relatively remote from its threaded end. Alternatively, stop 19 may be keyed to match an extension of flats 17, thus permitting its removal, but preventing it from contacting housing 11. The stop is larger in diameter than bolt 13, permitting insertion of bolt 13 through the hole in bracket 14 to a limited extent only. A nut 18 fits over the threaded portion of the bolt to secure it after it has been passed through bracket 14.

10 As nut 18 is tightened, bolt 13 is drawn through the bracket until the latter is engaged by stop 19.

To prevent the accidental loosening of nut 18 on bolt 13, a spring or lock washer designated by the numeral 20 is employed. Lock washer 20, more clearly illustrated in Fig. 4 is a piece of spring steel having arms 21 extending from the upper surface thereof to engage a pair of opposing faces of nut 18 and prevent its rotation. Beneath the lock washer 20 at its lowermost extremities are located a pair of nubs 22. Keyed washer 24 comprises an aperture 25 which is defined by a non-cylindrical surface conforming to the shape of bolt 13 at its milled flats 17. Keyed washer 24 also contains a pair of slots 26 in one face thereof on the opposite ends of its diameter.

In assembling the tensioning means bolt 13 is first inserted through housing 11. Stop 19 is then affixed to the bolt. Bracket 14 is then slid over the annular portion of bolt and attached to member 16. Next follows keyed washer 24, lock washer 20, and nut 18, respectively. Washers 27 may also be added to the assembly if desired.

30 When nut 18 is tightened, bolt 13 is drawn through bracket 14 until the latter contacts stop 19. Arms 21 engage a pair of faces of the nut causing lock washer 20 to rotate as nut 18 is turned. Nut 18 is rotated and lock washer 20 is compressed and rotated thereby until the desired tension on bail 10 and bolt 13 is achieved. The nut and lock washer are then turned to cause nubs 22 to be engaged in slots 26 of the keyed washer 24. When the floor-treating device is thereafter used and movement of bail 10 causes bolt 13 to rotate, keyed washer 24 rotates therewith causing lock washer 20 and nut 18 also to follow its rotation, thereby preventing the loosening of nut 18.

If the machine has a tendency to oscillate severely, the locking nut 18 is tightened, thereby increasing the tension between the bail and the housing of the machine,

45 making it easier to control and eliminating the wobble. It is appreciated that various other types of lock washers may be employed as well as a number of different types of brackets to secure the bail to the housing of the floor-treating unit.

50 In practice, it may be desired that a bearing or bushing surface be employed where the bail extension 13 is contiguous with the surface of the opening in bracket 14. This minimizes wear and facilitates the easy and even vertical movement of the handle of the floor-treating device.

55 Thus, through the practice of my invention, the severe oscillating movement or wobble commonly attributed to small rotary brush polishing and scrubbing machines can be readily and easily controlled. Any operator can, with 60 a minimum of effort, entirely eliminate this wobble, even when the handle of the machine is in a completely horizontal position.

65 While there are above disclosed but a limited number of embodiments of the structure of the invention herein presented, it is possible to produce still other embodiments without departing from the inventive concept herein disclosed, and it is desired therefore that only such limitations be imposed on the appended claim as are stated therein, or required by the prior art.

70 I claim:

An improved tensioning device for stabilizing a floor treating machine comprising in combination a forked bail,

a bolt integral with said bail extending inwardly from one extreme thereof said bolt being threaded at its free end and having keyways adjacent to the threading, a bracket with an annular opening circumscribing said bolt, means for securing said bracket to the floor treating machine to be stabilized, stopping means to restrict the extent to which said bolt passes through the annular opening of said bracket, a washer circumscribing said bolt and having keys for engagement in the keyways of said bolt said washer also having a slot in one face thereof, threaded means for securing said bracket and said washer on said bolt, and a lockwasher circumscribing said bolt on the bail side of said threaded means for locking said threaded means on said bolt, said lockwasher having nubs for en-

gaging the slot in said slotted washer whereby rotation of said bolt causes the rotation of the slotted washer, lockwasher and threaded means as a unit.
